CLAIM

The ornamental design for a battery charger, as shown and described.

DESCRIPTION

FIG. 1 is a top, front and right side perspective view of a battery charger, showing my new design;
FIG. 2 is a top, rear and left side perspective view thereof;
FIG. 3 is a bottom and left side perspective view thereof;
FIG. 4 is a front elevational view thereof;
FIG. 5 is a rear elevational view thereof;
FIG. 6 is a left side elevational view thereof;
FIG. 7 is a right side elevational view thereof;
FIG. 8 is a top plan view thereof;
FIG. 9 is a bottom plan view thereof;
FIG. 10 is a perspective view of the battery charger where the battery charger is in a folded state;
FIG. 11 is an exploded perspective view of the battery charger shown in FIG. 2;
FIG. 12 is an exploded perspective view of the battery charger shown in FIG. 10; and,
FIG. 13 is an enlarged view of portion 13 shown in FIG. 1. The broken lines in the drawings depict portions of the battery charger that form no part of the claimed design.

1 Claim, 13 Drawing Sheets
